UNITED STATES PATENT OFFICE.

JAKOB WACHOWIEZ, OF DETROIT, MICHIGAN.

NUT-CRACKING DEVICE.

1,041,531.

Specification of Letters Patent.

Patented Oct. 15, 1912.

Application filed April 16, 1912. Serial No. 691,083.

To all whom it may concern:

Be it known that I, JAKOB WACHOWIEZ, residing at Detroit, in the county of Wayne and State of Michigan, have invented certain new and useful Improvements in Nut-Cracking Devices, of which the following is a specification, reference being had therein to the accompanying drawing.

This invention relates to a nut cracking device, and the primary object of my invention is to provide a device that can be conveniently used for holding a mirror, a comb, a watch and collar buttons.

Another object of this invention is to provide a nut cracking device having a pivoted cracking lever that serves functionally as one of the cover plates of the device and the cover plate has a pivoted arm that permits of suitable leverage being obtained when cracking a nut.

A further object of this invention is to provide a household article consisting of comparatively few parts, inexpensive to manufacture and highly efficient for the purposes for which they are intended.

With the above and other objects in view the invention resides in the novel construction, combination and arrangement of parts to be hereinafter specifically described and 30 then claimed, and reference will now be had to the drawing, wherein:—

Figure 1 is an elevation of the inner side of one of the detached covers of the nut cracking device. Fig. 2 is an elevation of the body of the device with the cover thereof removed. Fig. 3 is an elevation of the inner side of another detached cover of the device. Fig. 4 is an elevation of the opposite side of the body from that shown in 40 Fig. 2. Fig. 5 is a side elevation of the device in an open position, and Fig. 6 is a longitudinal sectional view of the same.

A device in accordance with this invention comprises an oblong rectangular body 1 having longitudinal compartments 2 formed therein in which can be placed various kinds of articles. The formation of the longitudinal compartments 2 comprises a longitudinal rib 3, and this rib has a longitudinal slot 4 extending from a point centrally of the rib to the end of the body. The side edges of the rib 3, adjacent to the slot 4 are beveled, as at 5 whereby the fingers can be easily inserted in the compartments 2, and the rib 3 at a point intermediate the ends

thereof is cut away, as at 6 to provide clearance for the fingers.

Pivots mounted in the slot 4 by a transverse pin 7 is a ratchet bar or rack 8 adapted to normally fit in the slot 4, said 60 ratchet bar or rack being raised out of said slot by the fingers gripping the ratchet bar at the cut-away portion 6 of the rib 3. The rib 3, adjacent to the end of the slot 4 has recesses 9 and 10, the former accommodating 65 a small nut and the latter a large nut.

Pivots connected to one end of the body 1, preferably by hinged members 11 is a cracking lever 12 corresponding in plan to the shape of the body 1, said lever serving 70 functionally as a closure or lid for the compartments 2 of the body 1. The lever 12 has a longitudinal slot 13 with the walls of said slot connected by a web 14, said web being of a less depth than the walls of the 75 slot 13. The slot 13 extends from the free edge of the lever 12 to a point in proximity to the hinged edge thereof, and the inner edges of the slot 13, at the closed end thereof are notched or serrated, as at 15 to engage 80 the shell of a nut placed in either of the recesses 9 and 10. Pivots mounted in the open end of the slot 13 by a transverse pin 15 is an arm 16. This arm has the outer end thereof provided with a tooth 17 and the 85 inner end thereof is beveled, as at 18 to engage the end beveled wall of the slot 13, whereby the arm in a closed position can lie flush with the outer surface of the lever 12. The inner side of the arm 16 is cut away, 90 as at 19 to provide clearance for the web 14. Hinged to the opposite side of the body 1 and at the opposite end from the hinged members 11 is a cover or holder 20 having the inner face thereof provided with a recess 95 21 for a mirror 22, the recess 21 being located adjacent to the free end of said cover. The opposite end of the cover has a pocket 23 for a watch and the lower edges of the pocket are slotted, as at 24 to accommodate 100 collar buttons. To provide clearance for the heads of collar buttons, the body 1 is provided with openings 25, thereby permitting of the cover or lid being closed upon the body 1. The body 1 has the face thereof 105 confronting the cover 20 provided with an oblong recess 26 adapted to accommodate a comb.

When it is desired to use the nut cracker, the lever 12 is swung to an open position 110

and the ratchet bar or rack 8 raised. The arm 16 is then swung out of the slot 13, the nut to be cracked placed in one of the recesses 9 or 10, and then the lever 12 lowered. 5 As the lever 12 is lowered the free end of the ratchet bar or rack 8 is passed through the slot 13 between the web 14 and the pivoted end of the arm 16. The tooth 17 of the arm 16 is then placed in engagement with one 10 of the teeth of the ratchet bar and by lowering the outer end of the arm, suitable pressure can be brought to bear upon the lever 12 whereby the nut will be cracked or crushed. In this operation the pin 15 serves 15 as a fulcrum for the arm 16 and through the medium of the plurality of teeth carried by the ratchet bar or rack, nuts of various sizes can be cracked or crushed.

From the foregoing it will be observed 20 that the cover 20 serves functionally as a holder for various articles, also the body 1, and that when the three hinged parts of the

device are closed a rectangular structure is provided that is compact and can be easily and suitably ornamented.

25

What I claim is:—

In a nut cracking device, a body having recesses formed therein adapted to receive a nut, a rack having one end pivotally mounted in said body and adapted to have the opposite end thereof swung from said body, a cracking lever having one end pivotally connected to said body and adapted to swing upon said body, and an arm pivotally mounted in said lever and adapted to engage 30 said rack whereby suitable leverage can be brought to bear by said leverage upon a nut 35 in said body.

In testimony whereof I affix my signature in the presence of two witnesses.

JAKOB WACHOWIEZ.
